(No Model.)

F. M. TINKHAM.

EXTENSIBLE BED BOTTOM FOR IRON BEDSTEADS.

No. 593,824.

Patented Nov. 16, 1897.

UNITED STATES PATENT OFFICE.

FRANCIS M. TINKHAM, OF SPRINGFIELD, MASSACHUSETTS.

EXTENSIBLE BED-BOTTOM FOR IRON BEDSTEADS.

SPECIFICATION forming part of Letters Patent No. 593,824, dated November 16, 1897.

Application filed March 9, 1897. Serial No. 626,663. (No model.)

To all whom it may concern:

Be it known that I, FRANCIS M. TINKHAM, a citizen of the United States of America, residing at Springfield, in the county of Hampden and State of Massachusetts, have invented new and useful Improvements in Extensible Bed-Bottoms for Iron Bedsteads, of which the following is a specification.

This invention relates to bedsteads, and particularly to bed-bottoms for iron bedsteads, and has for its object the production of a bed-bottom longitudinally and transversely adjustable; and it consists in the particular construction shown and described in the accompanying drawings, specification, and claims.

In the drawings forming part of this specification, Figure 1 is a perspective view of a bed-bottom embodying my improvements. Fig. 2 is a transverse section of the same on line 2 2 on a somewhat smaller scale, and Fig. 3 is a perspective view of one end of one of the longitudinal frame-pieces.

Referring to the drawings, the bed-bottom construction therein illustrated consists of three sections, the central section comprising the longitudinal supports 2 2 2, having the transverse supports *a*, and the right and left hand sections comprising, respectively, the longitudinal supports 4 4, the transverse supports *b'*, and the longitudinal supports 3 3, and the transverse supports *b b*. The longitudinal supports 2, 3, and 4 of these sections consist of flat metal strips used edgewise and united together by the transverse supports used flatwise, and which are of substantially the same dimensions as the longitudinal supports, the ends of the latter being turned downward and riveted to the said supports 2, 3, and 4. The central section is made of these longitudinal supports equally spaced, and each of the side sections is made of two longitudinal supports of a width about equal to half the width of the central section. The ends of the longitudinal supports of the central section on one end thereof and the end of the outer longitudinal support of the side section on one end thereof are given a quarter-turn twist, as at *x*, and these ends are then turned up and over to form the hooks 2^a for engaging with the end rail of the bed-

stead. The opposite ends of said supports 2, 3, and 4 are provided with the hooks 2^b, which are separate from and adjustable on the said longitudinal supports 2, 3, and 4 on the ends 55 of said supports opposite the ends having the hooks 2^a thereon. The construction of the said adjustable hooks 2^b is illustrated in Fig. 3 in perspective. The ends of the supports 2, 3, and 4 are cutoff, as shown, and the hooks 60 2^b have a slot 7 punched through them, through which the ends of the said supports are passed, and a pin 7^a or other convenient method for preventing them from slipping off from said supports is employed. 65

In constructing this bed-bottom the central section is first made. The side sections are then completed, with the exception that the inner one of the two longitudinal supports 3 3 and 4 4 is left unattached to its several transverse supports. The inner one of the two supports 3 and 4 of each of the side sections is then passed under the transverse supports of the central section, as shown in Fig. 1 of the drawings, and the transverse supports of 75 the side sections are then riveted to each of the inner longitudinal sections which are located under the transverse supports *a a* of the central section, thereby attaching the side and central sections together, but permitting the side sections to be moved transversely on said central section to adjust the bed-bottom to any width of bedstead to which it may be desired to apply it. 70

In order to prevent endwise movement of 85 the side sections on the central sections, the transverse supports on each end of the side sections are placed outside of and close up to the transverse support *a* on each end of the central section. To securely hold the side 90 sections level with central section, the clips 6 6 are riveted to the side sections near their inner corners, as shown. These clips, securely fastened to the support *b*, project inward and over the supports *a a*, close to the 95 longitudinal support which lies under said supports *a a*. The transverse supports on each end of the central section are thus engaged on their upper and under sides by the end sections, and supported by such engagement and by the bearing of the supports *b* and *b'* on the upper edge of the outside longi- 100

tudinal supports of the central section, yet having a free sliding movement thereon transversely thereof. Fig. 2 shows in dotted lines the extreme position to which the side sections may be moved toward each other on the central section.

A bed-bottom constructed according to my invention as herein described is one easily adapted to any of the ordinary iron bedsteads and is adapted to be closely fitted to the side rails of said beds and affords perfect support for either a woven-wire mattress or any of the coiled-spring constructions in common use. It is of small cost and of very light weight and can be closely folded for shipment.

Having thus described my invention, what I claim, and desire to secure by Letters Patent, is—

1. In a bed-bottom, a central stationary section consisting of the parallel longitudinal supports 2 which are united by the transverse supports *a*, which extend in opposite directions from the central longitudinal supports 2, combined with longitudinal supports 3, 4, which are united in pairs by the transverse supports *b*, *b'*, which extend across the tops of the outer longitudinal supports 2, and the supports 6 which catch upon the tops of the transverse supports *a*; the longitudinal supports being provided with hooks upon their ends, and the transverse supports 3, 4, being horizontally adjustable in relation to the supports 2, whereby the width of the bed-bottom

can be increased or decreased at will, substantially as shown. 35

2. In a bed-bottom, a stationary longitudinal support 2, provided with hooks 2^a at one end, the transverse supports *a* which connect the supports 2 rigidly together, and the removable hooks 2^b, which are applied to the outer ends of the longitudinal supports, combined with the removable longitudinal supports 3, 4, the transverse supports *b*, *b'*, which unite them in pairs, and which supports catch over the top edges of the two outer stationary longitudinal supports 2; the supports 6 secured to the inner ends of the transverse supports *b*, *b'*, and which supports catch over the tops of the stationary transverse supports *a*, and the pins 7^a which prevent the removable hooks from becoming detached, all combined and arranged to operate, substantially as specified. 40

3. A bed-bottom for iron bedsteads consisting of a central section, separate side sections transversely movable on said central section, means of engagement between said side and central sections for holding them in the same plane, and fixed and longitudinally-adjustable end supports on the opposite ends of said sections, substantially as described. 45 50 55 60

FRANCIS M. TINKHAM.
